UNITED STATES PATENT OFFICE.

BENJAMIN LOT PARKER, OF GENOA, ILLINOIS.

MEANS FOR OPERATING CAMERA-SHUTTERS.

1,254,931.

Specification of Letters Patent. Patented Jan. 29, 1918.

Application filed July 13, 1916. Serial No. 108,969.

To all whom it may concern:

Be it known that I, BENJAMIN L. PARKER, a citizen of the United States, residing at Genoa, State of Illinois, have invented a new 5 and useful Improvement in Means for Operating Camera-Shutters, of which the following is a specification.

My invention relates to self-acting means for operating a camera shutter and is so designed as to be readily and quickly attached 10 to the shutter either directly or through the ordinary wire release now in use.

It is a further object to produce a device of this class so designed that it may be set 15 in motion by an exceedingly low electrical current.

It is a further object to produce a device of this class so designed as to prevent repeating or re-operating of the shutter without 20 first being reset.

The above and other features of advantage and capabilities will become apparent from a detail description of the accompanying drawings, in which I have illustrated a 25 practical embodiment of the invention, but the construction there shown is to be understood as illustrative only, and not as defining the limits of the invention.

Figure 1 is an elevational view of a camera 30 era with an operating means embodying my invention applied thereto.

Fig. 2 is a longitudinal sectional view of the operating means shown in Fig. 1, and

Fig. 3 is a sectional view taken approximately on the line 3—3 of Fig. 2.

Referring to the drawings in detail, all the operating means are shown mounted in a rectangular casing 10, which casing is provided with a spring clip 11 for readily and 40 quickly securing the casing to a platform or support of the usual camera.

Pivotedly connected at one end with the lugs 12, which are secured to the end of the casing, is a slotted trip lever 13, which normally rests at its opposite end on an armature 14, which armature is pivoted at its lower end in the lugs 15. Adjacent to the armature 14 is a pair of electromagnets 16 arranged one above the other, the windings 50 of which are connected in such a manner as to produce a north and south magnetic pole at the pole tips when the current is applied. The ends of the windings terminate at the

posts 17 and 18, which posts are in turn connected to a battery or other source of current supply not shown.

Pivotedly connected at one end to the casing 10 is a spring pressed operating lever 19, which lever extends outwardly through a slotted opening in the casing, with its free 60 or opposite end connected by means of a wire 20 to the camera shutter as shown. The operating lever 19 is by a slot and pin connected to the trip lever 13. From this it will readily be seen that when the armature 65 14 is drawn inwardly by means of the current when applied, the trip lever 13 is released, thus allowing the free end of the operating lever 19 to be forced downwardly by means of the coil spring 21, and as the free 70 end of the operating lever is moved downwardly it operates the shutter of the camera, this it can do either when connected directly to the shutter by the wire 20 as shown, or when connected integrally by means of the 75 usual wire release 22.

The device is particularly desirable for the reason that the lever connections are so arranged that it will require but very little power or current to trip the lever 13 and 80 start the mechanism to work, and for the further reason that it is absolutely impossible to have a repeat or re-operation of the shutter without first resetting the operating mechanism. To reset the mechanism all 85 that is necessary is to grasp the free end of the operating lever 19 and raise it upwardly in its slotted opening in the casing 10, until the free end of the trip lever 13 has been raised sufficiently high as to rest on the upper edge of the armature 14, in which position it is again ready for operation. The free end of the trip lever 13 engages the armature and as the lever moves upwardly 90 restores the armature to its normal position. 95

While I have described the operating means as being used in connection with a camera shutter, it is quite obvious that it may be used in connection with other devices and for other purposes.

I claim:

In a trip mechanism, a casing, a horizontal operating lever pivotally mounted at one end in said casing, the opposite end being adapted to upward and downward movement, a 105 trip lever mounted in said casing having a

slidable connection with said operating lever near the free end thereof, an armature in said casing upon which the free end of said trip lever normally rests and electrically operated means for disconnecting said armature from the free end of said trip lever for the purpose set forth.

Copies of this patent may be obtained for five cents each, by addressing the "Commissioner of Patents, Washington, D. C."

In witness whereof, I hereunto subscribe my name to this specification in the presence of two witnesses.

BENJAMIN LOT PARKER.
